BOTTLE CARRIER

Leon Dolgins, 328 Lantana Ave., Englewood, N.J.

Filed Sept. 24, 1965, Ser. No. 87,435

Term of patent 3½ years

(Cl. D58—26)

FIG. 1

FIG. 3

FIG. 1 is a side perspective view of a bottle carrier embodying my new design;

FIG. 2 is a perspective view showing the side opposite that seen in FIG. 1;

FIG. 3 is an end elevational view thereof.

I claim:

The ornamental design for a bottle carrier, substantially as shown.
